UNITED STATES PATENT OFFICE.

JULIUS SWANBERG, OF CHICAGO, ILLINOIS, ASSIGNOR, BY MESNE ASSIGNMENTS, TO
ROBERT CHELTON, OF CHICAGO, ILLINOIS.

PENCIL.

Application filed April 2, 1924. Serial No. 703,590.

This invention relates to a pencil, and particularly one which provides improvements in the construction of mechanical type pencils.

It is an object of this invention to provide a mechanical type pencil wherein an operating part of the lead-propelling mechanism affords the necessary frictional drag for said mechanism.

It is a further object of this invention to provide a mechanical type pencil having an improved eraser-holding structure associated therewith.

It is another object of this invention to provide a pencil embodying an improved lead magazine structure.

It is an important object of this invention to provide an improved type of mechanical pencil which is neat in appearance, easily re-filled with lead, efficient and convenient in operation, durable and capable of being economically manufactured.

Other and further important objects of this invention will be apparent from the disclosures in the specification and the accompanying drawings.

On the drawings:

Fig. 1 is an elevation view of a pencil embodying the principles of this invention.

Fig. 2 is a longitudinal central section with parts in elevation slightly enlarged taken through the pencil of this invention.

Fig. 3 is a view similar to Fig. 2 with the lead-propelling mechanism shown in section and the operating cap and closure structure in elevation.

Fig. 4 is an enlarged fragmentary detail sectional view illustrating the attachment of the lead-feeding tube to the rotatable cap member.

Fig. 5 is a slightly enlarged section on the line 5—5, of Figure 2.

As shown on the drawings:

The reference numeral 1 indicates a usual pencil casing which may be formed of any suitable material, but which in the present instance, is preferably formed of hard rubber or similar material. Said casing 1 is provided with a usual conical point 2 and is longitudinally recessed, having a passaged tip member 3 engaged in said recess, said member 3 being provided with a shoulder abutting the end of the casing 1 at the conical point 2, and being suitably split as indicated at 4 to resiliently engage a lead 5 extending therethrough in the usual manner.

The tip member 3 has a tubular extension 6 extending through the passage in the conical point 2 to an enlargement 7 of said passage, where it is flared outwardly as indicated at 8, to facilitate the dropping of a lead there-through. The end of the casing 1 opposite the conical point 2 is internally threaded to receive a closure plug member 9 which is preferably provided with a knurled flange 10 engaging the end of the casing 1 and projecting slightly from the wall thereof to facilitate the unscrewing of the closure member 9. Rotatably mounted in said closure member 9, and extending axially through the casing 1, and abutting a shoulder 11 in the tip member 3, is a lead feeding and guiding tube 12. Axially movable in said tube 12 is a lead feeding plunger 13, which is provided at its inner end with a projecting member 14, which extends outwardly through a slot 15 in said tube between the coils of a helical member 16 surrounding the tube inside the pencil casing. The outer end of said helical member 16 is permanently secured to the closure member 9, so that said helical member is normally non-rotatable, and the lower end of said helical member abuts a thrust washer or flange member 17 extending outwardly from the tube 12 and secured thereto at a point intermediate its ends. The helical member 16 is preferably slightly compressed relative to its longitudinal axis, so that the frictional engagement of the end thereof with the flange member 17 affords a desired frictional drag to the rotation of said tube. The ends of the slot 15 in the tube 12 limit the movement of the member 14 toward and from the point of the pencil, a wire plug 18 permanently secured in the outer end of said tube 12, as shown in Figure 4, acts to strengthen the end of the tube at the joint between the closure member 9 and a rotatable cap member 19, which is rotatable on said closure member, and which is secured to said outer end of the tube 12. The recess 7 in the casing 1 is enlarged adjacent the helical member 16 to afford an enlarged recess 20, there being a shoulder 21 between said recesses 7 and 20, as clearly shown in Fig. 2. A magazine for extra leads is provided for by said recess 20, said magazine being divided into three compartments by similar stamped metal members 22, which are placed together in the manner shown in Figs. 2 and 5,

to enclose the helical member 16, the outwardly extending ribbed portions 23 of which engage each other and also engage the inner wall of the casing 1 in the recess 20. 5 These stamped metal members 22 are assembled in the position shown in Fig. 5 and forced into the casing, being frictionally held therein by the engagement of the ribs 23 with the walls of the casing. The extra 10 leads in position in the magazine rest on the shoulder 21 and are positioned in the magazine as indicated in Fig. 5, said extra leads being represented by the reference numeral 24. Leads may be inserted in the pencil 15 either from the outside through the tip 3, or from the inside by dropping the same into the tube 6, or they may be dropped into the end of the tube 12 when the same is removed from the pencil, the end of said tube 12 being 20 countersunk at 12^A for this purpose.

This invention also provides an improved eraser structure which is associated with the rotatable cap member 19, and which acts to removably secure an eraser 25 thereto. 25 For this purpose said cap member 19 is provided with an internally threaded recess at its outer end, which is adapted to receive a split exteriorly threaded bushing 26, in which the eraser 25 is mounted. Said eraser 30 is mounted in an outwardly converging recess in said bushing, so that when the bushing is revolved in the cap 19 the eraser is firmly held in association therewith. A knurled flange 27 is formed on the bushing 26 to facilitate the engagement thereof with the cap member 19, the inner side of said flange resting on the end of the cap member when the same is in operative position. It 35 will be apparent from the foregoing description that this invention provides a mechanical pencil which is of exceedingly simple construction, and in which the leads may be readily replenished. When said leads are 40 in position in the pencil, the rotation of the cap 19 of course causes an axial movement of the plunger 13, due to the engagement of the projecting member 14 on said plunger, with the helical member 16, which is held 45 stationary by the closure member 9. To remove the mechanism from the pencil and to 50 gain access to the extra lead magazine, it is only necessary to unscrew said closure member 9, as will be evident.

55 Worn erasers 25 may be easily replenished by removal of the split bushing 26 and the insertion of a new eraser therein from the inner end thereof. As previously explained, the slight compression which is given to the helical member 16 acts to afford the necessary frictional drag to the operation of the 60 pencil. The magazine with a plurality of compartments affords a convenient means for keeping a supply of leads of different color, distinctive colors being placed in separate chambers. 65

I am aware that numerous details of construction may be varied through a wide range without departing from the principles of this invention, and I therefore do not purpose limiting the patent granted otherwise than necessitated by the prior art. 70

I claim as my invention:

1. In a pencil, a casing having a conical point, a closure member removably secured in the other end of said casing, a tube 75 rotatably engaged through said closure member and extending through the casing to the interior of the conical point, an operating cap secured to the tube and engaging said closure member, a helical member surrounding the tube and secured at one end to said closure member, a member secured to the tube movably engaging the other end of said helical member, a lead propelling plunger in the tube, and means on said plunger engaging the helical member so that rotation of the tube actuates the plunger. 80

2. In a pencil, a casing having a conical point, a closure member removably secured 90 in the other end of said casing, a tube rotatably engaged through said closure member and extending through the casing, and rotatably contacting the same in the interior of said conical point, an operating cap secured to the tube and engaging said closure member, a helical member surrounding the tube and secured at one end to said closure member, a member secured to the tube movably engaging the other end of said helical member, said member being so positioned as to slightly compress said helical member, a lead propelling plunger in the tube, and means on said plunger engaging the helical member so that rotation of the tube actuates 95 the plunger. 100

3. In a pencil, a casing, a lead-propelling mechanism rotatably mounted therein, and resilient helical means in the casing cooperating with said lead-propelling mechanism 110 to propel the lead, said helical means being in engagement under compression with a portion of said lead-propelling mechanism, whereby to retard rotation of the mechanism. 115

4. In a pencil, a casing, a lead-propelling mechanism rotatably mounted therein, a helical member held against rotation within the casing, a lead-feeding plunger rotatable 120 with said mechanism and lengthwise movable therein, coacting with the said helical member to propel the lead, said helical member being resilient and being under compression lengthwise between a portion 125 of the casing and a portion of the lead-propelling mechanism whereby to retard rotation of the mechanism.

In testimony whereof I have hereunto subscribed my name.

JULIUS SWANBERG.
